UNITED STATES PATENT OFFICE.

CHARLES M. FOWLER, OF SALEM, MASSACHUSETTS.

FIRE-ESCAPE.

SPECIFICATION forming part of Letters Patent No. 398,826, dated March 5, 1889.

Application filed November 21, 1888. Serial No. 291,480. (No model.)

To all whom it may concern:

Be it known that I, CHARLES M. FOWLER, a citizen of the United States, and a resident of Salem, in the county of Essex and State of 5 Massachusetts, have invented new and useful Improvements in Fire-Escapes, of which the following, taken in connection with the accompanying drawings, is a specification.

This invention relates to improvements in 10 portable fire-escapes, and it is carried out as follows, reference being had to the accompanying drawings, wherein--

Figure 1 represents a sectional front elevation of the device, showing the covering-plate 15 as removed. Fig. 2 represents a cross-section on the line X X, shown in Fig. 1; and Fig. 3 represents a cross-section on the line Y Y, also shown in Fig. 1.

Similar letters refer to similar parts whenever they occur on the different parts of the drawings.

1 represents a metal case or box, which may be of any desired size or form and provided with a detachable plate or cover, 2, as shown 25 in the drawings.

3 is the life-line, the upper end of which is to be secured in a suitable manner to the window sill, casing, or other part of the building or furniture within the room when the device 30 is to be used, and for this purpose the upper end of said life-line may be provided with a hook, ring, or other suitable or well-known fastening device, which is, however, not shown in the drawings. The life-line 3 passes loosely 35 through vertical perforations 4 and 5 in the upper and lower portions, respectively, of the case 1 and cover 2, as shown in Figs. 1 and 3, and it is to be made long enough to extend 40 from the place where it is secured to the ground, or nearly so.

Within the box 1 is pivoted at 6 the main brake-lever 7, to the inner end of which is attached the rope or chain 8, to which the person that is to be lowered is secured by means 45 of a suitable belt or other device usually employed in portable fire-escapes, such device being, however, not shown in the drawings. The main brake-lever 7 has on its under side two brake projections, 9 and 10, one on each 50 side of the fulcrum 6, as shown in Fig. 1, the object of which will hereinafter be set forth.

Below the brake projection 9 is arranged with- 55 in the case 1 the stationary projection 11, preferably provided with an upper concave surface, as shown in Fig. 1. Below the brake projection 10 is journaled within the case 1 on a pin-screw or rivet, 12, the guide-pulley 13, as shown in Figs. 1 and 3. I prefer to guide the rope 3 at this place over the pulley, as shown; but this is not essential, as a sta- 60 tionary pin or projection may be used for this purpose without departing from the essence of my invention.

14 is another stationary pin or guide projec- 65 tion within the case 1, around which the life-line 3 is guided, as shown in Fig. 1. To the outer end of the main brake-lever 7 is at- 70 tached the cord 15, having a suitable button or handle, 16, secured to its lower end, as shown in Fig. 1, by means of which the de- 75 scending person can manipulate the said main brake-lever for the purpose of regulating the frictional resistance on the life-line, and thus to regulate and control the speed of the descent, or stop it altogether, as circumstances may require.

17 is a secondary or auxiliary brake-lever piv- 80 oted at 18 to the case 1 and provided in its outer end with a cord, 19, to the lower end of which is secured a suitable handle or button, 20, as shown in Fig. 1, by means of which said aux- 85 illiary brake-lever can be manipulated for the purpose of breaking the life-line 3 at the place where it passes round the projection 14, thus enabling the operator to still further control the frictional resistance on the life-line and 90 consequent speed of descent.

In using the invention the upper end of the life-line 3 is secured in a suitable manner to any convenient stationary object, and the free 95 end of such line is thrown down to the ground, or nearly so. The person that is to descend is then secured in a suitable manner to the rope 8, or a belt or equivalent device attached thereto, and when so suspended the weight of 100 the party will cause the projection 9 on the brake-lever 7 to press and bear on the life-line 3, where it passes over the stationary pro- 105 jection 11, as shown in Figs. 1 and 2, thus preventing the device from sliding downward on the said life-line until the pressure of the 110 brake-lever 7 is relieved, which is done by the

operator taking hold of the cord 15, and by pulling downward on it causing the said lever 7 to be swung on its fulcrum 6, and the pressure of the projection 9 on the line 3 consequently relieved, allowing the device and the person attached to it to gradually descend.

Should the operator pull too hard on the cord 15, the brake projection 9 will be entirely, or nearly so, relieved from the line where it passes over the stationary projection 11, and the line will be compressed or held between the brake projection 10 and the pulley or projection 13. Should the operator while descending let go his hold on the main brake-lever cord 15, the brake projection 9 will be automatically pressed against the rope 3 where it passes over the stationary projection 11 by the weight of the said operator, thus arresting the descent until the brake-lever 7 is again manipulated, and so on. It will thus be seen that the person descending has a perfect control of the device, can regulate at pleasure the speed of the descent, and can arrest the descent at any desired place, in a manner as hereinabove fully set forth.

Although the lever 7 is sufficient for the purpose of regulating and controlling the frictional resistance on the life-line 3, I prefer in practice to use in connection with it the auxiliary brake-lever 17, partly for the purpose of employing an additional means for braking on the life-line and thereby controlling and regulating the frictional resistance on said line, and also for the purpose of balancing the device by enabling the operator to

grasp with one hand the brake-lever cord 15 and with the other the auxiliary brake-lever cord 19, and by holding onto both, and thus manipulating both the main and auxiliary brake-levers, a perfect control of the device is obtained.

Having thus fully described the nature, construction, and operation of my invention, I wish to secure by Letters Patent, and claim—

1. The herein-described fire-escape, consisting of the frame 1 2, adapted to slide on the life-line 3, and having rope-guides 11, 13, and 14, combined with the brake-lever 7, pivoted to the frame and having the brake projections 9 and 10, and the rope or chain 8, attached to said brake-lever, as and for the purpose set forth.

2. The herein-described fire-escape, consisting of the frame 1 2, adapted to slide on the life-line 3, and having rope-guides 11, 13, and 14, combined with the pivoted main brake-lever 7, having the supporting rope or chain 8 attached to it and having the brake projections 9 10, as described, and the auxiliary brake-lever 17, substantially as and for the purpose set forth.

In testimony whereof I have signed my name to this specification, in the presence of two subscribing witnesses, on this 17th day of November, A. D. 1888.

CHARLES M. FOWLER.
